UNITED STATES PATENT OFFICE.

ADRAIN NUTTING, OF GREENVILLE, TEXAS, ASSIGNOR OF NINETEEN-TWENTIETHS TO BENJAMIN D. MARTIN, JOHN C. O'NEAL, ROBT. C. DIAL, JOHN M. ELLIS, HENRY WAGNER, FRANK L. GAZETTE, AND THOMAS E. BYRD, ALL OF SAME PLACE.

CAR-CO尤PLING.

SPECIFICATION forming part of Letters Patent No. 330,416, dated November 17, 1885.

Application filed June 11, 1885. Serial No. 168,387. (No model.)

To all whom it may concern:

Be it known that I, ADRAIN NUTTING, a citizen of the United States, residing at Greenville, in the county of Hunt and State of Texas, have invented new and useful Improvements in Car-Couplings, of which the following is a specification.

This invention relates to that class of car-couplings in which the draw-head incloses a pivoted dog or hook that is normally seated by a spring, and provided with a chain or other elevating device for raising it from its engagement with the coupling-link.

The invention consists in certain peculiarities of construction, as hereinafter set forth, whereby are secured efficiency and reliability of action, with freedom from injurious jar or vibration in the coupling-hook and its connections without impeding the necessary play of the link.

In the annexed drawings, illustrating the invention, Figure 1 is a vertical longitudinal section of my improved car-coupling. Fig. 2 is a horizontal section of the same. Fig. 3 is a vertical cross-section on the line xx of Fig. 1.

Referring to these drawings, the numeral 1 designates a recessed draw-head having a flaring mouth, 2, and provided with vertical perforations 3, for receiving an ordinary coupling-pin, if required. In the narrow portion of the draw-head is inserted a transverse pivot-pin, 4, that forms a fulcrum for the coupling hook or dog 5, which rests normally on the floor of the draw-head or on the inserted end of a link, 6, as the case may be. The inner walls of the draw-head mouth are formed in vertical and horizontal section, as shown in Figs. 1 and 2. It will be seen that on each vertical side, as shown in Fig. 2, the inner surface of the draw-head tapers or curves gradually backward to the points 7, and then curves inward more abruptly to form abutments 8, that limit the inward movement of the link. These abutments 8 are located on each side of the pivoted dog 5, about midway between its pivotal and free ends. The upper portion or roof of the draw-head is provided with a nearly triangular recess 9, which is formed longitudinally in the center of the approximately con-

vexed roof or upper wall, 10, the form of which is shown by dotted lines in Fig. 1. This recess 9 intersects in front the upper vertical perforations, 3, and at the rear it gradually merges with the narrow longitudinal recess 11, in which the coupling-hook 5 is pivoted. The front portion of the lower wall or floor, 12, is inclined upward and inward, and provided with a recess, 13, directly above the lower vertical perforation, 3. This recess 13 is for the reception of the hooked end 14 of the coupling-dog 5 when the latter is lowered. It will be observed, however, that the recess 13 is sufficiently deep to prevent contact therewith by the hooked point 14, which is thus preserved from injury by battering. Extending across the floor of the draw-head, at the rear upper edge of the recess 13, is a transverse ridge or projection, 15, which is sufficiently elevated above the forward extended portion of the horizontal floor of the longitudinal recess 11 to form a rocking point for the link, as hereinafter explained. The coupling hook or dog 5 is normally seated by means of a spiral spring, 16, arranged in a vertical diagonal recess, 17, formed in the roof of the draw-head. The lower end of this spring 16 rests on the upper surface of the coupling hook 5, near its forward end, and is held in place by a guide-pin, 18, inserted therein. The coupling-hook may be raised against the action of this spring, when required, by means of a chain, rod, or other elevating device attached in an eye, 19, formed in the upper forward corner of said hook. By forming the forward end of the hook 5 with a curved or rounded surface, as shown, it is capable of being raised automatically by the pressure of the entering link. An abutment, 20, for the forward end of the hook 5, is formed by the front lower edge of the recess 9, in which said hook moves, said abutment thus serving to take the strain of the draft, and thereby relieving the pivot 4, on which the hook is fulcrumed.

It will be observed that the construction and arrangement of the socketed draw-head and its accompaniments is such that they can be readily detached, so that new hooks and springs can be substituted with ease whenever re-

quired. In order to remove these parts it is only necessary to withdraw the pivot-pin 4, when the coupling-hook 5 and spring 16 will drop forward, and can be taken out at once. 5 On reinserting the parts the spring 16 is first passed up into its socket or recess 17, the guide-pin 18 is inserted into the upper edge of the hook 5, and the latter is then passed into the draw-head and its inner end elevated 10 behind the abutment 20, at the forward lower end of the recess 9. By this movement the guide-pin 18 will pass readily within the lower end of the coiled spring 16, and at the same time the pivotal end of the hook 5 is brought 15 into position to be engaged with its pivot-pin 4, which is passed through the side of the draw-head. The link 6, when engaged with only one draw-head, has its engaged end forced down behind the ridge or projection 15 by 20 the pressure of the hook 5 and its spring 16. It is thus not only securely held from accidental disengagement, but has its outer end elevated at an angle usually sufficient to enable it to engage readily with an opposing draw- 25 head of greater height than the one with which it is already connected. Should it, however, be necessary to connect with a draw-head of equal or less height, the outer end of the engaged link can be readily depressed by simply 30 elevating the engaging dog slightly through its attached chain, rod, or other device, so as to relax the pressure on the engaged end of the link and permit its free outer end to drop to the required point. When the 35 train is in motion, the link will have a rocking movement or play at each end on the ridges or projections 15, under the yielding pressure of the spring-seated hooks or dogs. The flaring side walls of the draw-head will 40 also allow the link to have all necessary side play in turning curves or otherwise. The coupling-dog 5, however, being pivoted in the narrow longitudinal recess 11, is thereby held 45 from lateral movement, and so affords a firm point of engagement and draft for the link. As the free or hooked end of the dog 5 is sufficiently deep or of sufficient length vertically to bear against the rear side of the abutment 20 at all times when engaged with a link, it is 50 obvious that the draft will thereby be distributed, so as to relieve the pivot-pin 4 of all injurious strain.

What I claim is—

1. In a car-coupling, the combination, with 55 a recessed draw-head having rear lower abutments to limit the backward movement of the link, a forward upper abutment to take the pressure of the coupling-hook, and a trans- 60 verse ridge or projection for the link to rock

upon, of a vertically-movable coupling-hook 60 pivoted in a narrow recessed portion of said draw-head, and a spring located in a diagonal recess formed in the upper part of the draw-head and bearing on the upper side of the hook near its forward end, substantially as 65 described.

2. In a car-coupling, the combination, with a draw-head having a narrow longitudinal recess for receiving the pivoted end of a coupling-hook, a narrow triangular recess for permitting an upward swinging movement of the hook, an abutment or bearing for the forward end of the hook, rear abutment to limit the backward movement of the link, and a transverse ridge on which said link can rock, of a 70 pivoted coupling-dog having a vertically- 75 swinging movement in the narrow triangular recess at the rear of the forward abutment, a spiral spring located in a diagonal recess in the upper part of the draw-head and bearing 80 on said coupling-dog near its forward end, and a guide-pin for said spring, substantially as described.

3. In a car-coupling, the combination of the draw-head 1, having lower rear abutments, 8, upper forward abutment, 20, triangular recess 9, and a recess, 13, for receiving the lower hooked end of a coupling-dog, the link 6, the pivoted dog 5, carrying a guide-pin, 18, near its forward end, and a 85 spiral spring, 16, surrounding said guide-pin, 90 substantially as described.

4. In a car-coupling, the combination of a recessed draw-head having abutments 8 and 20, and a transverse ridge, 15, of a link, 6, 95 adapted to rock on said ridge, a pivoted coupling-hook, 5, carrying a diagonally-projecting pin near its forward end, and a spiral spring, 16, arranged diagonally above the coupling-hook and surrounding said pin, substantially 100 as described.

5. In a car-coupling, the combination of the draw-head 1, having a narrow longitudinal recess, 11, the upper recess, 9, lower recess, 13, transverse ridge 15, rear abutments, 105 8, and forward abutment, 20, the coupling-hook 5, pivoted in the narrow recess 11 and adapted to swing vertically in the recess 9, and with a hooked end for engaging the recess 13 and abutment 20, the link 6, and the spring 110 16 in recess 17, substantially as described.

In testimony whereof I affix my signature in presence of two witnesses.

ADRAIN NUTTING.
